PERFORATING DEVICE

Lawrence V. Whistler and Sanford A. Whistler,
Kenmore, N. Y.

Application October 27, 1941, Serial No. 416,691

13 Claims. (Cl. 164—118)

Our invention relates to perforating equipment for use in punch presses.

One of the objects of our invention is to provide perforating equipment whereby the stock to be perforated may have the perforations therein more closely spaced apart than has heretofore been possible; also to provide perforating units for this purpose which may be individually positioned with respect to other units in an assembly of units, and at the same time measurably reduce the setting-up time, all with assurance of more accuracy than has been possible heretofore.

Another object of our invention is to associate perforating units with die and punch-holder retaining-plates prepared for the assembly of perforating units, so that the units may be conveniently and quickly applied to such plates with certainty that perfect alinement of co-acting members of each unit is had, and with further assurance that the centers of the punch and die elements of the assembly of units are positively and accurately spaced apart according to predetermined measurement; also whereby the punch and die units can be very closely centered one with respect to another or others, depending on the number of punch and die units employed in an assembly.

A further object of our invention is to employ a template fashioned with the various perforations therein accurately spaced apart and centered with respect to each other in exactly the manner in which the stock to be perforated is intended to leave the press, either as a complete article or for further manipulation thereon, such template being utilized to prepare our punch and die-holder retaining-plates so that these plates can be drilled simultaneously while set one upon the other to form holes for setting-up pins and holes for dowel or pilot pins forming part of or at least projecting from the two members of each perforating unit, such dowel pins having their longitudinal axes alined with the axes of the die in the die-holder retaining member and the punch of the punch-holder retaining member.

A further object of our invention is to form the punch and die-holder retaining-plates in the manner last described, and also to form therein holes to receive fastening means by means of which punch and die-members are fastened to such plates, such fastening means being preferably in the form of screw bolts which have a definitely spaced relation to the longitudinal axes of the dowel or pilot pins so that when the holes are drilled and tapped in said punch and die-holder retaining-plates, and such plates are definitely

spaced apart and otherwise relatively positioned by means of setting-up devices, it is only necessary to position the punch and die-members on these plates according to the pairs of holes provided therein, one of each pair being for a dowel or pilot pin of the punch-member and the other for the fastening screw bolt, while the co-acting pair of holes in the co-operating plate is likewise used to position the die-member thereto by means of its dowel or pilot pin and fastening screw bolt.

A further object of our invention is to provide perforating equipment including therein punch and die-holder retaining-plates which are used as a pair and applied or secured in any suitable manner within a die-set or press, one to the shoe of the die-set or to the bed of the press, as the case may be; and the other to the ram of the die-set or press, such plates having removably secured thereto the punch and die-members, respectively, of a perforating unit or a plurality of such units, so that when applied in the die-set or press, setting-up means comprising setting-up pins are only necessary to be entered in setting-up holes formed in the two retaining-plates, with assurance that when these plates are fastened in place within the die-set, or the press, all perforating units will function as intended; not only as to their spacing, but also in relation to the punch and die-members of each perforating unit, since these punch and die-members, after once being positioned on the retaining-plates, may be retained thereon, or they may be removed therefrom individually or as a complete set-up and if required for use in the same relation may be quickly positioned and fastened on the plates.

With the above and other objects to appear hereinafter, our invention relates to the novel method of producing and applying perforating equipment; to the novel means employed in establishing such equipment; also to the construction, arrangement, and combination of parts to be hereinafter described and more particularly pointed out in the sub-joined claims.

In the drawings,

Fig. 1 is a sectional elevation of a die-shoe having our improved perforating equipment attached thereto, the sectional part being taken through line 1—1, Fig. 2, looking in the direction of the arrow crossing said line.

Fig. 2 is a horizontal section taken on line 2—2, Fig. 1.

Fig. 3 is a detached perspective view of one of the setting-up pins and its spacing bushing.

Fig. 4 is a detached perspective view of a tem-

plate having holes or perforations therein, according to which the punch and die-holder retaining-plates will be simultaneously drilled. These holes or perforations are shown arranged in a different manner than those illustrated in other figures of the drawings, with a view of better disclosing how our perforating units may be employed under any of various arrangements.

Fig. 5 is a plan view of the die-holder retaining-plate, the punch-holder retaining-plate being similar in appearance and construction, with the exception that the openings for the dowel or pilot pins and the securing screw-boots are oppositely disposed with relation to the longitudinal center of these plates.

Fig. 6 is a vertical section through a perforating unit and portions of the punch and die-holder retaining-plates to which the members of the perforating unit are secured; showing also portions of the shoe of a die-set or the bed of a press and the ram of a die-set or press.

Fig. 7 is a central longitudinal section through a co-operating couple of retaining-plates in association with a template according to which the plates are to be drilled, these parts being arranged in laminated form and illustrating the plates after being drilled to conform to the holes in the template.

Fig. 8 is a detached side elevation of the stripper unit.

Fig. 9 is a horizontal section looking down, taken on line 9—9, Fig. 6.

Fig. 10 is a detached perspective view of one of the die-holders or members and the die therein.

Fig. 11 is a detached perspective view of the clip for retaining the stripper unit around the punch of the punch-member.

In the drawings we have associated our punch and die equipment with a die-set having a ram and a shoe or bed, the ram being illustrated as movable toward and from the bed, but it is to be understood that where hereinafter a ram and a shoe or bed are referred to, it may also mean the ram and bed of a punch press.

In the drawings, the reference numeral 12 designates the shoe of a die-set, and 13 the ram thereof, the shoe having guide posts 14 extending upwardly therefrom and the ram guide sleeves 15 secured therein and projecting downwardly therefrom into which the guide posts 14 are slidably fitted. The ram has a shank 16 secured thereto by means of which it may be fastened to the ram of a press.

In the use of our equipment, we employ a punch-holder retaining-plate 17 which may be secured to the under side of the ram 13 in any approved manner, and a die-holder retaining-plate 18 is seated against the shoe of the die-set and fastened thereto in any approved manner. These retaining-plates are provided with a pair of setting-up pin-holes 19 which may be referred to as master pilot-holes, and in some instances, particularly where the article or stock to be perforated is of considerable size requiring comparatively large retaining-plates, such holes may be increased in number, for instance as shown by dotted lines 19' in Fig. 5. These retaining-plates have also any number of holes 20, 21 drilled therein or therethrough which are respectively referred to as dowel or pilot-pin holes and holes for securing elements. The holes 20 and 21 are arranged in pairs and may be formed at any desired points in the retaining-plates. In Figs. 2 and 5 some of these pairs of holes are shown in close proximity to each other, and in the par-

ticular embodiment of our invention illustrated, the securing elements are of larger diameter than the dowel or pilot-pins, both of which will be hereinafter more particularly described. The holes 19, 20, and 21 are drilled in the retaining-plates in accordance with holes 19^a, 19^b, and 19^c formed in a template 22. The holes 19^a determine the locations of the setting-up pins, to be hereinafter described, and the holes 19^b and 19^c the locations of the aforesaid dowel or pilot-pins and the securing elements, respectively.

In the act of preparing the punch and die-holder retaining-plates, two sheets or plates of steel or other suitable metal of the desired outline are mounted one upon the other, and the template placed over the so arranged retaining plates, thereby forming a somewhat laminated structure, as shown in Fig. 7; the upper lamina, or the template to be more particular, having been preformed with the various holes which are to be duplicated in each of the plates or two lower laminae by drilling through them while using the holes in the template as guides or gauges. The plates when drilled in conformity with the template, serve as the punch and die-holder retaining-plates. This laminated structure in which the laminae are clamped or temporarily fastened together in any suitable manner while drilling the two lower laminae, may be easily disassembled after removing the clamps therefrom or otherwise separating them, and these plates 17 and 18 are then used in the manner shown in Fig. 1. The holes 20 and 21 are used respectively for positioning and axially alining the punch and die of each punch-and-die unit, or more particularly each perforating unit, and fastening the members of the unit to the plates, as will more particularly appear hereinafter.

In order to derive the benefits of this equipment to its highest degree, the punch-member 23 and the die-member 24 each have a comparatively long and narrow body portion 25, 26, respectively, which together with their respective parts form a perforating unit. The body portion 25 of each punch-member has a pilot or dowel-pin 27 driven or otherwise secured therein so as to project a distance from its upper surface, while the body portion of each die-member 26 has a pilot or dowel-pin 28 driven or otherwise fastened therein and projecting a distance beneath its lower surface. The pilot or dowel-pins 27 and 28 are fitted into the openings 29 in the punch-holder retaining-plate 17 and die-holder retaining-plate 18, respectively, and the axes of these pilot or dowel-pins determine the axis of a perforation to be formed in the stock introduced between the punch and die-members.

The body portion 25 of each punch-member is bored out from the bottom, as at 29, and from one end thereof, as at 30, the bore 30 being tapped to receive a securing screw 31 which is threaded firmly against a reduced portion of a punch 32 entered in the bore 29 from the bottom of the body portion 25. In this manner the punch is firmly but removably held in place. This body portion has its upper or plate-contacting surface at a perfect right-angle to the axis of said punch.

33 designates a stripper-unit comprising a spiral spring 34 and a stripper-disk 35 to which the lower end of said spring is welded. Each stripper-disk has an opening 36 therethrough into which the lower end or punch terminal 37 of the punch is entered, this punch terminal being normally retained within the opening 36.

when the spring 34 is fully expanded. It may here be stated that punches having various size punch terminals may be fastened into the body portion of the punch-member, and when a punch having a punch terminal of larger diameter than shown in Fig. 6 of the drawings is required, a stripper-unit whose disk has an opening 38 of larger diameter is necessarily employed. This stripper-unit, being positioned around the punch, is retained thereon by means of a clip 38 having two arms arranged at a right angle one to the other so that one is horizontally disposed and enters the spiral spring between two convolutions thereof while the other is vertically disposed and has a screw hole 39 punched therethrough which is aligned with a tapped opening 40 in the body portion 28. Through the screw hole 39 a securing screw 41 is passed which is threaded into the tapped opening 40, thus firmly securing the clip 38 in position to retain the stripper-unit around the punch.

The body portion of each punch-member 28 also has an opening 42 therethrough which is enlarged at its lower end, as at 43. A securing screw 44 is passed through said opening and threaded into one of the holes 21 formed in the punch-holder retaining-plate 17, the head 45 of said securing screw firmly engaging the shoulder formed in the hole 42 by enlarging the lower end thereof.

The body portion 26 of the die-member 24 has a die-bushing or retainer 46 welded or otherwise secured to its upper surface, and it has an opening 47 formed therein which is reduced in diameter or transverse dimension at its lower end to form an upwardly-facing shoulder or die-seat 48, and in this die-bushing or retainer a die 49 is placed which has a punch-receiving hole therethrough conforming at its upper end to the punch terminal of the co-acting punch 32, so that when stock is placed between the punch-member and the die-member of one or more perforating units, it is perforated by the punch. The slug or slugs pass through the die and the die-bushing or retainer and enter a curved slug discharge passage 50 which opens to one end of the body portion 26 and delivers the slugs onto the die-holder retaining-plate 18, from which the various slugs accumulated thereon may be removed under air pressure, or in any other manner.

Like the punch-member of each perforating unit, the die-member is also provided with an opening or screw hole 51 which may be enlarged at its upper end, and in this hole is placed a securing screw 52 which is passed through the body portion of the die-member and has its lower end threaded into one of the tapped holes 21 formed in the die-holder retaining-plate 18. It is of course understood that each of the pilot or dowel pins 27 and 28, which may be more particularly referred to as locating pins for a perforating unit, are axially aligned with the punch 32 and die 49 of the unit to which these several parts belong. The under surface of the body portion of said die-member is at a perfect right angle to the axis of the die 49. Thus, when placing the locating pins in the holes 20 of the respective retaining-plates, assurance will be had that the holes punched in the stock will be exactly as located in the template 22, and since each of these holes 20 is paired with a tapped hole 21, definitely spaced center to center with the space so provided exactly that between the axes of the punch and securing screw of the

5 punch-member and exactly that between the axis of the die and the extended axis of the securing screw of the die-member 24, registration of the punch and die cannot be otherwise than perfect, and the mere placement and securing in place of the two members of a perforating unit assures such perfection.

10 By reason of the punch and die members being secured to retainer plates in the manner described, they may be easily removed when certain holes are to be omitted in some stampings, or they may be replaced with other similar members designed for punching larger or smaller holes, without removing the retaining plates from the die-set; such requirement being common in 15 certain lines of work. This replacement may also be effected when it is found that certain punches or dies require redressing, since no individual punch member or die member which may be found functioning improperly can now be removed and replaced without disturbing any of the other punch or die members of the assembly and without the necessity of removing the retainer plates, or even disturbing their relative positions.

20 Due to the fact that the width of the body portions of the respective members of each perforating unit need be no wider than the diameter of the spring 34 of the stripper unit in the case of the punch-member, and no wider than 25 is necessary to form the die-bushing or retainer 46 in order to receive the die and by reason of the punches and dies being located at one of the ends of the body portions, it is quite apparent 30 that stock can be punched or otherwise perforated with the centers of the perforations exceedingly close to each other and that the series 35 of punch and die elements can attain such close relationship by movement relatively in three directions.

40 Although we have illustrated slight spaces between the several punch-members, and also between the several die-members, these members can be placed directly in contact one with another, side to side or end to end, so that the 45 openings in the stock being punched can be even closer than illustrated by the spacing of the holes 28 and 21 shown in Fig. 5.

46 The two retaining-plates 17 and 18 preferably have the various perforating units secured thereto before positioning the same in the die-set, because the various holes formed in these retaining plates definitely determine the locations and respective centers of the perforating units. If desired, however, these retaining-plates may be positioned in the die-set and the perforating units applied after positioning and fastening the retaining-plates in place. In either case, however, we employ master setting-up devices to accurately position the plates relatively. In Fig. 1 we have shown the punch and die holder retaining-plates separated a definite distance by utilizing the setting-up devices 53 for this purpose. In the particular setting-up device shown, master setting-up pins 54 are entered through spacer-bushings 55 with opposite ends of these pins projecting from the bushings and entered in the setting-up pin-holes 19 in the two spaced-apart retaining-plates. The end surfaces of each bushing 55 are parallel to each other and at a perfect right angle to its master setting-up pin 54, so that the lower end surface of each bushing rests upon the die-holder retaining-plate 18 while the punch-holder retaining-plate 17 rests against the upper end surface of said bushing. In this manner all open-

ings in the two retaining-plates are matched one with another and the matched holes arranged in perfect vertical alinement, and assurance is had of the retaining-plates being in perfect parallelism during the act of adjusting said plates relatively. Therefore all parts carried or supported by these retaining-plates are positioned in exact accordance with the template 22, according to which the stock or material to be operated upon will be perforated.

The two retaining-plates 17 and 18, with or without the perforating units attached thereto, which may be a matter of choice, are secured to the ram and shoe of the die-set in any approved manner. If perforating units are secured to these retaining-plates before securing the latter in the die-set, the two members of each unit will be in perfect registration when said plates are secured in place. If the perforating units are secured to the retaining-plates after fastening the latter in place, assurance will be had that when such units are fastened to the retaining-plates, perfect registration of the two members of each unit must be had. After fastening the two retaining-plates 17 and 18 to their respective backings or foundations, as the ram and shoe of the die-set may be termed, the ram may be elevated so that the space between the under surface of the punch-holder retaining-plate and the upper surface of the die-holder retaining-plate will be greater than the length of the master setting-up pins 53, after which the two or more master setting-up devices, depending on the number it is desired to use and the size of the retaining-plates, can be easily removed. In using the term "master setting-up devices" we include the master setting-up pins 54 and the spacing bushings 55, or any other device serving the same purpose.

Although in Fig. 1 we have shown the master setting-up devices in use, the spacing between the punch-member and the die-member of the several perforating units shown may be that of greatest opening of the press or die-set during the operation of perforating, since this space would include the stock or material to be placed between the members of the several perforating units so that it will be perforated in accordance with a pre-arranged plan, as for example illustrated by the holes 20 and 21, shown in Fig. 5; or as a further example, according to the holes shown in Fig. 4, which although a view of a template, shows a different arrangement of holes, and when using such template, punch and die-holder retaining-plates will be drilled accordingly.

The disposition of the holes shown in Figs. 4 and 5 merely illustrate that any desired arrangement for setting up the perforating units may be had. As clearly illustrated in Figs. 1 and 2, more perforating units are to be employed than shown therein, since each hole 20 exposed in Fig. 2 is to receive the pilot or dowel-pin 28 of a die-member and the co-operating hole 21 the screw 52 by means of which said member is secured to the die-holder retaining-plate 18. Fig. 2 therefore clearly illustrates that there are to be two parallel longitudinal rows of perforating units, each row comprising eight units which are slightly spaced equal distances apart; that there is to be a transverse row of perforating units, five in number, disposed at a right angle to said two parallel rows, and all spaced different distances from each other, and that there are also to be two separate perforating units placed between said two longitudinal rows of units and the transverse row. 75

It has, however, been found advisable, to better illustrate the purpose of this invention and to more particularly set forth its application, to omit some of the perforating units in Figs. 1 and 2.

In Fig. 6 the die and punch-members of the perforating unit therein shown are illustrated with the ram of the die-shoe slightly lowered to show the stripper-unit in contact with the upper surface of the die-bushing 48 and the die 49, and the lower end of the punch 32 about to enter the die. It is of course understood that when such relative positions of the parts take place, the stock or material to be punched rests upon the die-bushing and die, and that the stripper-unit may have its lower end in contact with the stock or material, and that further downward movement of the ram of the die-set will result in the punch piercing such stock or material and the slug passing down through the die, the lower end of the die-bushing, and forward through the body portion 24 of the die-member so that it may be delivered onto the die-holder retaining-plate 18.

From the foregoing it will be apparent that the holes 20 in each retaining-plate are paired with the holes 21 in such plate, and that these holes so used in pairs are for the purpose of positioning the punch-member and the die-member on the retaining-plate and securing the same thereto, each pair of such holes being associated with a single punch-member or a single die-member. It will also be apparent that the holes 20 in each retaining-plate match or coincide with similar holes 20 in the co-operating plate, and that this is also true with respect to the holes 21, and that these holes 20 and 21 are matched or positioned so that their axes are coincident in pairs by the employment of the major pilot-pins or the setting-up devices, as hereinbefore explained. It should furthermore be apparent that the major pilot or setting-up devices bring about the proper relationship and disposition of the holes 20 in one plate with respect to the holes 20 in the other plate and also the holes 21, and that the holes 20 are used with pilot elements or pins, also referred to as dowel-pins, to position the punch and die-members of each perforating unit in their proper relative positions, and that the holes 21 are utilized to receive securing screws which are axially aligned insofar as the two members of each perforating unit are concerned.

Since the pilot holes 20 of the retaining-plates 17 and 18 are used to axially locate the punches and dies of the perforating units, these holes in a broader sense may be termed locating means, and of course under this term as used in the claims, the punches and dies of each perforating unit may be definitely located with respect to their position on the plate or plates by means other than the pilot holes 20 in the plate and the pilot-pins 27 and 28 forming part of the perforating units. The die-bushing or retainer 48 may be constructed cylindrically as shown in Figs. 1 and 2 of the drawings, or may be made square as shown in Fig. 10, or given any other information.

While we have shown the use of a template for drilling the holes in the two retaining-plates 17 and 18, these holes may be formed in any other approved manner, such as by marking the centers of the holes on a sheet or plate adapted to be used as a retaining-plate and drilling and reaming the holes to desired size, and by then

utilizing the plate so drilled as a pattern for a second plate, in which case the two plates will be firmly secured together by means of clamps or otherwise, and the imperforate plate drilled through the openings of the prepared plate. Various other means may be used to accomplish this purpose.

Having thus described our invention, what we claim is:

1. In equipment for perforating sheet metal or the like, a pair of punch and die-holder retaining-plates each provided with at least two comparatively large holes and with comparatively small holes spaced apart according to the perforations to be formed in a sheet of metal, the comparatively large holes in said retaining plates being arranged in pairs with a hole of each pair in the punch-holder retaining-plate axially aligned with a hole in the die-holder retaining-plate and with the smaller holes in each plate paired and axially aligned with like holes in the other retaining-plate, a master setting-up device between said retaining-plates having parts fitting in each pair of said comparatively large holes to temporarily hold said retaining plates in definitely spaced-apart relation and to properly position said retaining-plates relatively, and perforating units each having a punch-member and a die-member, said members having setting-up elements forming part thereof fitting in the comparatively small holes in said retaining-plates so as to position the punch and die of each perforating unit in axial alignment, and means to secure the punch of each perforating unit to one of said retaining-plates and the mating die to the other retaining-plate.

2. In equipment for perforating sheet metal or the like, a pair of punch and die-holder retaining-plates having pilot holes in each retaining-plate paired and axially aligned with pilot holes in the other retaining-plate and with additional holes in each retaining-plate paired and axially aligned with holes in the other retaining-plate, the last-mentioned pairs of holes being screw-threaded, a master setting-up device co-operating with said retaining-plates to temporarily position the latter in definitely spaced-apart relation and to position the holes in said retaining-plates relatively in the positions mentioned, and perforating units having pilot pins entered in said pilot holes and securing screws passed through said units and threaded into the threaded holes of said retaining-plates.

3. In equipment for perforating sheet metal or the like, a pair of spaced-apart punch and die-holder retaining-plates provided with at least two comparatively large holes and with comparatively small holes spaced apart according to the perforations to be formed in a sheet of metal, the comparatively large holes in said retaining-plates being arranged in pairs with a hole of each pair in the punch-holder retaining-plate axially aligned with a hole in the die-holder retaining-plate and with the smaller holes in each retaining-plate paired and axially aligned with holes in the other retaining-plate, a master setting-up device having parallel upper and lower end surfaces with parts projecting from said end surfaces adapted to be entered in said comparatively large openings so as to position the punch-holder retaining-plate in proper relation to the die-holder retaining-plate and to position the smaller holes in said retaining-plates with the axis of each pair of said smaller holes in alignment, the lower end surface of each master set-

ting-up device resting upon one of said retaining-plates and the upper end surface thereof being in contact with the other retaining-plate, and perforating units each comprising a punch-member and a die-member, both members being provided with pilot pins entered in the pilot openings of said retaining-plates to position the punch in axial alignment with the die and with means to secure said punch and die-members to their respective retaining plates.

4. In equipment for perforating sheet metal or the like, two punch and die retaining-plates provided with master setting-up openings and smaller pilot openings drilled simultaneously therein while said plates are arranged in superimposed relation, master setting-up means interposed between said retaining-plates while in spaced relation to position the punch-holder retaining-plate in proper relation to the die-holder retaining-plate and to position the smaller pilot openings in said retaining-plates with the axes of each pair of said smaller holes in alignment, and perforating units each having a punch-member and a die-member, one for co-action with one of said retaining-plates and the other for co-action with the other retaining-plate, each of said members having a projecting pilot portion entered into a pilot opening in one of said plates with the punch of each perforating unit axially co-incident with the die of said unit, and means to secure the punch-member of each perforating unit to one of said retaining-plates and the die-members of said unit to the other retaining-plate.

5. In equipment for perforating sheet metal or the like, a pair of plates adapted to be secured respectively to the ram and shoe of a die-set, each of said plates having a pilot hole and a tapped hole, a perforating unit comprising a punch-member and a die-member, said punch-member having a narrow elongated body portion provided with a pilot pin adapted to be entered in the pilot hole of one of said plates and with a bore axially co-incident with the tapped hole in said last-mentioned plate, a securing screw passed through the bore of said body portion from beneath the latter and threaded into said tapped hole, said pilot pin and bore being spaced apart longitudinally of said body portion and the latter having a second bore extending upwardly from its lower end parallel with said first-mentioned bore and spaced from the latter along the length of said body portion, and a punch entered in said second bore and projecting downwardly therefrom.

6. In equipment for perforating sheet metal or the like, a pair of spaced-apart plates adapted to be secured, respectively, to the ram and shoe of a die-set, said plates having pilot holes therein arranged in close proximity to each other and in pairs with each pilot hole in one plate axially aligned and paired with a pilot hole in the other plate, perforating units comprising punch and die-members, each punch-member having a comparatively long and narrow punch body portion and a pilot projection near one end adapted to enter a pilot opening in one of said plates, said punch body portions being arranged in parallel relation against said last-mentioned plate and having securing means near their other ends accessible from the space between said plates for fastening the said body portions to said last-mentioned plate, each punch body portion having a punch removably secured therein axially co-incident with the pilot pro-

jection thereof, and each die-member having a comparatively long and narrow die body portion provided with a pilot projection near one end thereof adapted to enter a pilot opening in the other of said plates, means near the other end of said die body portion also accessible from the space between said plates to secure the die body portion to said last-mentioned plate and a die secured to said die body portion axially coincident with the pilot projection of the latter and with the punch of said punch-member, said long and narrow body portions permitting the punch and die of each perforating unit to be closely spaced apart by movement relatively in any of three directions.

7. The method of producing perforating equipment which consists in forming holes in two plates exactly duplicated in number and spacing, in utilizing certain of said holes as pilot holes and a like number as securing holes in utilizing the plates so formed in spaced relation with the pilot holes of each axially aligned with corresponding pilot holes in the other, in applying perforating units to said plates having a punch-member for one plate and a die-member for the other, each member having a pilot element adapted to be entered in a pilot hole of its co-operating plate to position the punch of said punch-member and the die of said die-member axially in alignment with each other and with the axes of the holes in which said pilot elements are entered, and in setting-up said plates to space the same apart and relatively position said plates so as to assure axial alignment of said corresponding pilot holes in said plates, and to utilize said securing holes for securing said plates as so spaced.

8. The method of producing perforating equipment which consists in establishing locating means for perforating units on two plates so that said locating means are exactly duplicated in number and spacing for such plates, in utilizing the plates so formed in spaced relation with the locating means of each aligned with corresponding locating means of the other, in employing setting-up devices interposed in spaced-apart relation between said plates to position said plates so as to establish a true alignment of corresponding locating means of both plates while spaced apart, and in applying perforating units comprising punches and dies to such plates and utilizing corresponding locating means of said plates to position the punch of each perforating unit axially in alignment with the die thereof and in true alignment with corresponding locating means of said plates, and in moving said setting-up means out of coaction with said plates after fastening the latter to machine parts with which said perforating equipment is to be operated.

9. The method of producing perforating equipment which consists in forming holes in two plates exactly duplicated in number and spacing, in employing setting-up means to position said plates in exact parallelism, space the same a definite distance apart and bring corresponding holes of said plates in axial alignment, in applying perforating means to said plates and utilizing corresponding holes to position the punch and die of each perforating unit in axial alignment with said corresponding holes, in employing means to

5 fasten the perforating units to said plates when so positioned, in the use of fastening means for fastening said plates to parts of a machine employed to operate said perforating equipment, and in moving said setting-up devices out of coaction with said plates to permit operation of said machine.

10. The method of producing perforating equipment which consists in establishing punch-and-die locating means for two plates exactly duplicated in number and spacing, in employing setting-up means in co-operation with said plates to temporarily position the same in parallelism and to space the same apart while positioning corresponding locating means of said plates in alignment in planes at right-angles to said plates so that perforating devices will be attached to said plates according to the locating means of said plates and so that the punches and dies of said perforating devices are spaced apart in conformity with the spacing of the locating devices of each of said plates.

11. The method of producing perforating equipment which consists in establishing punch-and-die locating means for two plates exactly duplicated in number and spacing for each plate by forming spaced-apart holes in each of said plates with the holes of one plate matching those of the other, in placing setting-up devices between said plates with each setting-up device having portions temporarily holding said plates in alignment so as to position matching holes of said plates in axial alignment and to position said plates in parallelism and in desired spaced-apart relation, and in applying perforating units to opposing faces of said plates with the punch and die of each aligned with aligned locating means.

12. In perforating means for perforating sheet metal or the like, a punch member comprising a body portion having a punch secured therein and projecting therefrom, a stripper-unit surrounding said punch and comprising a spiral spring bearing at one end against the underside of said body portion, a stripper disk welded to the lower end of said spring and surrounding the punch terminal of said punch, and a clip fastened to said body portion and having a part extending between adjacent convolutions of said spring to hold said stripper-unit in position around said punch.

13. In perforating means for perforating flat sheet material, a punch holding element, a die holding element, a punch member comprising a body portion secured to said punch holding element and having a punch removably secured therein and projecting therefrom, a stripper unit surrounding said punch and comprising a spiral spring bearing at one end against the underside of said body portion, a stripper disk secured to the lower end of said spring and surrounding the punch terminal of said punch and a clip fastened to said body portion and having a part extending between adjacent convolutions of said spring to hold said stripper unit in position around said punch, and a die member comprising a body portion secured to said die holding element and a die carried by said body portion for co-action with said punch.
